CARBURETOR

Robert F. Bracke, Chicago, Ill.

Application May 16, 1939, Serial No. 273,853

1 Claim. (Cl. 261—41)

My invention pertains to carburetors and is more particularly concerned with carburetors of the fuel lift type.

In non-fuel lift carburetors for automotive use, it is common to provide a main fuel supply nozzle and an idling jet. This idling jet is customarily located on the engine side of the throttle valve and takes care of the fuel requirements of the engine during idling operation. A needle valve or other adjustment means is commonly provided to adjust this idling jet. Both the main fuel supply nozzle and the idling jet receive their fuel requirements from the float bowl of the carburetor.

Various attempts have been made to provide a fuel lift carburetor with such an idling jet. In fuel lift carburetors, however, the float bowl of the carburetor is maintained under a degree of suction sufficient to draw fuel thereinto from the main fuel supply tank usually located at the rear of the automobile. At full throttle operation, the degree of suction obtaining in the carburetor float bowl is greater than that obtaining at the discharge end of the idling jet, with the result that there occurs a back feed of fuel and air from the idling jet to the float bowl of the carburetor. This is disadvantageous in that it destroys the delicate balance necessary to proper operation of a fuel lift carburetor.

An object of my invention is to provide a fuel lift carburetor with an idling jet which overcomes the foregoing disadvantages.

Another object is to provide a fuel lift carburetor with an idling jet whose fuel supply is automatically cut off when the throttle valve reaches a predetermined position.

Another object is to provide an idling jet mechanism for a fuel lift carburetor, which mechanism is equally applicable to single-nozzle and multi-nozzle carburetors.

Another object is to provide a simplified and improved idling jet mechanism for a fuel lift carburetor.

Another object is to provide a carburetor which is economical to manufacture, which will provide long and trouble-free service, and wherein the various control mechanisms may be independently adjusted.

Other objects and advantages will become apparent as the description proceeds.

This application is a continuation in part of my copending application Serial No. 136,544 filed April 13, 1937, patented June 13, 1939, Patent No. 2,162,056.

In the drawings, Figure 1 is a diagrammatic

view of a carburetor embodying one form of my invention. In this diagrammatic view the relative positions of the parts are distorted but their functional relationship is easy to follow; and

Figure 2 is a sectional view of a carburetor embodying a second form of my invention.

Referring to the drawings, I have illustrated a carburetor having a float bowl 10 adapted to be connected by means of a pipe 12 with the main fuel supply tank of an automobile or similar machine. The quantity of fuel admitted to the float bowl 10 is regulated by the usual float-controlled inlet valve 14. In the particular carburetor shown, the float bowl 10 supplies fuel to a pair of main fuel feeding nozzles 16 and 18, each of which is illustrated as discharging into a separate mixing chamber 20 or 22.

Air is admitted to the mixing chambers 20 and 22 by way of a pivoted air valve 24 illustrated as being biased in one direction by weight 26 and connected with a dashpot 28 which prevents fluttering of the air valve 24. A pair of throttle valves 30 and 32 illustrated as mounted on a common shaft 34 control communication between the mixing chambers 20 and 22 and the inlet manifold of the engine to which the carburetor is attached. The throttle valve shaft 34 is provided with an arm 36 adapted to be connected to the usual foot and hand controls of an automobile.

Arm 36 is also connected to a link 38 and lever 40, the latter being connected to a second lever 42 by way of bolt 44 and interposed spring 46 for eliminating lost motion from the connection between the two levers which may be mounted on a common pivot pin 48 or pivoted separately as desired. A link 50 connects lever 42 with rod 52 extending into the float bowl 10 and slidably mounted in a guide 54. The lower end of the rod 52 is connected to a base 56 carrying an economy pin 58 which passes through an orifice 60 and regulates the quantity of fuel supplied to the nozzles 16 and 18.

The base 56 also operates the piston 62 of an accelerator pump. This piston has a bolt 64 slidably received in an opening in the base 56 and provided with a head 66 limiting separation of the piston and base under the influence of the spring 68 which yieldably advances the piston 62 when the throttle valves are opened.

The piston 62 has an inlet valve 70 controlling a passage through the piston and through which fuel from the float bowl 10 enters the cylinder 72. When the throttle valves are opened suddenly, the advance of the piston 62 discharges fluid from the cylinder 72, past the outlet valve 74 and

through passages 76 and 78 to accelerator jets 80 and 82 respectively.

I have illustrated my carburetor as provided with idling jets 84 and 86 controlled respectively by needle valves 88 and 90. The idling jets 84 and 86 communicate with vertical passages 92 and 94 respectively. Each vertical passage is provided with a small diameter air inlet 96 and a small bore 98 immediately above its main idling jet. The bores 98 form auxiliary idling jets and although smaller in diameter than the bores 96, prevent back bleed therethrough in the event the needle valves 88 and 90 are entirely closed.

The vertical passages 92 and 94 communicate with ducts 100 and 102 respectively, leading to a chamber 104 communicating with an annular recess 106 in the rod 52. The chamber 104 is provided with a very small air vent 107 to prevent siphoning of fuel from the float bowl through the idling jets. The part of the rod 52 below the recess 106 has a diameter two-thousandths of an inch less than the internal diameter of the guide 54 which permits the desired amount of fuel to flow from the float bowl 10 upwardly along the rod 52 to recess 106, chamber 104, and thence to idling jets 84 and 86 during idling operation of the engine.

The float bowl 10 is maintained under sub-atmospheric pressure by a booster Venturi tube 108 having its restricted throat connected with the upper part of the float bowl by way of passage 110. The booster Venturi tube 108 communicates with atmosphere through ports 112 and 114, and air inlet 116. The ports 112 and 114 are in a disc 118 which may be rotated to choke the booster Venturi tube 108 and thereby facilitate starting in cold weather.

The booster Venturi tube 108 discharges through passageway 120 into both mixing chambers 20 and 22. The discharge from the booster Venturi tube 108 passes through a restricted orifice 122 and is regulated by a tapered pin 124 connected with the air valve 24.

The operation of the idling jets of the carburetor shown in Figure 1 is as follows: When the engine is idling, the throttle valves 30 and 32 are closed or nearly so and a high degree of suction is exerted on the idling jets 84 and 86. This degree of suction is sufficiently greater than the suction obtaining in the float bowl 10 to draw fuel from the float bowl upwardly along the rod 52 in the small clearance between this rod and the guide 54, thence into chamber 104 and through ducts 100 and 102 and passages 92 and 94 to the idling jets. As the throttle valves are opened, the degree of suction obtaining at the idling jets and available to draw fuel thereto from the float bowl 10 decreases. When the throttle valves are opened to such a degree that the idling jets are no longer necessary, as the main fuel nozzles 16 and 18 are alone capable of supplying all fuel needed by the engine, the degree of suction obtaining at the idling jets has so decreased that it is no longer sufficient to overcome the resistance of the restricted passageway between the rod 52 and guide 54 and no further fuel is supplied to the idling jets.

As the throttle valves 30 and 32 are opened wider and wider, the degree of suction obtaining at the idling jets 84 and 86 is still further decreased and at some point in the opening of the throttle valves, the suction obtaining at the idling jets just balances that existing in the float bowl 10. Further opening of the throttle valves means that the degree of suction obtain-

ing in the float bowl is greater than that obtaining at the idling jets 84 and 86. This would normally produce objectionable back bleed from the idling jets to the float bowl, but this is prevented by the resistance of the small clearance between the guide 54 and rod 52 which functions as a restriction to prevent such back bleed. This structure is interposed between the float bowl and idling jets and flow of fuel through this restriction is automatically regulated by suction in accordance with engine requirements.

In the carburetor shown in Figure 2, I have further simplified the carburetor structure by partially combining the accelerating pump mechanism with the idling jet mechanism. In this figure I have shown a carburetor having a main air inlet 150 communicating by way of air valve 152 with dual mixing chambers 154, each of which is provided with a main fuel feeding nozzle 156 and a throttle valve 158 on a common shaft 160.

The throttle valve shaft 160 is interconnected with a link 162 in a manner similar to that of Figure 1 whereby opening of the throttle valve raises the link 162. The lower end of this link is pivotally connected to a rod 164 and a spring 166 is located in the tubular link 162 and between the two pivotal connections thereof to eliminate lost motion.

The lower end of the rod 164 is secured to a plate 168 carrying an economizer pin 170 for regulating the fuel supply to the nozzle 156. The plate 168 has an opening for slidably receiving the cylinder 172 of an accelerator pump. A spring 174 surrounds the cylinder 172 and urges it upwardly with respect to the plate 168, upward movement of the cylinder being limited by washer 176 held in place by snap ring 178. The lower end of the cylinder 172 is provided with a passage controlled by a ball inlet valve 180 whereby the cylinder is supplied with fuel from the carburetor float bowl 182.

The accelerator pump has a stationary piston 184 provided with a packing 186 urged against the cylinder wall by an annular spring 188. The piston 184 has a discharge passage 190 which is restricted by a plug 192 provided with a very small opening such as the bore formed by a No. 73 drill. The upper end of the passage 190 forms a seat for a gravity actuated valve 194 controlling communication between the passage 190 and a duct 196 leading to accelerating jets 198.

The duct 196 also communicates with a pair of vertical ducts 200 each leading to an idling jet 202 controlled by a needle valve 204. Valves 180 and 194 prevent back bleed through duct 196.

It will be understood that the air valve 152 is provided with a weight or spring for urging this valve toward closed position and the valve is shown as being connected to a dashpot 208 to reduce valve fluctuation. The air valve 152 also controls a tapered pin 210 located in a restricted orifice 212 through which the booster Venturi tube (not shown) discharges. This booster Venturi tube serves to maintain sufficient suction in the float bowl 182 to draw fuel thereinto from the main fuel supply tank as described more fully in connection with Figure 1.

In the operation of the carburetor of Figure 2, the throttle valves 158 assume the position shown when the engine is idling. During such idling, the high degree of suction existing below the throttle valves is sufficient to raise valves 180 and 194 associated with the accelerator pump and draw fuel from the float bowl, past these

valves and through the restricting plug 192, thence through duct 196 and ducts 200 to the idling jets 202. When the throttle valves 158 are opened to such a degree that all fuel requirements of the engine can be adequately cared for by the main fuel feeding nozzles 156, the degree of suction at the idling jets 202 has decreased to such an extent that it is insufficient to draw fuel past the valves 180 and 194 and restriction 192. It will be noted that the accelerator jets 198 function as anti-siphoning air inlets for the duct system leading to the idling jets 202.

When the throttle valves are opened suddenly, the spring 174 is compressed and urges the accelerator pump cylinder 172 upwardly. This forces fuel through the restriction 192 in the piston, past valve 194, and through duct 196 to the accelerator jets 198 through which is discharged most of the fuel forced from the accelerator pump as a result of the sudden opening of the throttle valves. A small proportion of this fuel may also be discharged through the idling jets 202, but this is not objectionable. In fact, the interconnection of the idling jets with the accelerator jets has a material advantage in addition to simplification of the carburetor structure.

Throughout the range of operation of the idling jets the duct system leading to the accelerator jets 198 is maintained full of fuel. Practically all acceleration starts from this range so that at the start of each acceleration the passages leading to the accelerator jets 198 are filled with fuel whereby discharge of fuel from the accelerating jets starts simultaneously with the opening movement of the throttle valve. This results in instantaneous response of the engine. In carburetors in which the accelerator pump mechanism is entirely separate from the idling jet system, it is common for the accelerator pump system to be partially drained of fuel when opening movement of the throttle valves first begins. This results in a lag in the response of the engine to the accelerating movement of the throttle valve.

The modification shown in Figure 2 has a further advantage over that shown in Figure 1. In the embodiment of Figure 1 a small amount of air leaks down along the rod 52 and into chamber 104, even though that part of rod 52 above groove 106 is designed to fit tightly in the carburetor body. As a result of this leakage, an emulsion of fuel and air is supplied to the idling jets 84 and 86. This emulsion, however, is not necessarily uniform and sometimes contains slugs of fuel which offer greater resistance to flow through the passages to the idling jets than does the emulsion. The presence of such slugs in these passages therefore temporarily reduces the

degree of suction existing in the float bowl 10 and creates uneven idling of the engine.

This disadvantage of the embodiment shown in Figure 1 is eliminated in the embodiment of Figure 2. In Figure 2 the ducts 196 and 200 are so located and designed that the only infiltration of air into these ducts is through the accelerator jets 198 which correspond to the air inlet bores 96 of Figure 1 and which do not produce the objectionable characteristics resulting from leakage of air past the rod 52 of Figure 1.

While I have illustrated both embodiments of my invention as being applied to carburetors having two fuel feeding nozzles, it will be understood that both embodiments of my invention are equally adapted for application to a carburetor having only a single fuel feeding nozzle or any number of such nozzles. It is also to be understood that my invention is not limited to the details shown but may assume numerous other forms.

The claims herein are directed broadly to subject matter disclosed but not claimed in my said Patent No. 2,162,056, and also specifically to the two embodiments shown in the drawings of the instant application.

I claim:

In a fuel lift carburetor of the class described the combination of a float bowl adapted to hold a quantity of fuel, a booster Venturi tube for maintaining said float bowl under sub-atmospheric pressure, a main fuel feeding nozzle supplied with fuel from said float bowl, conduit means connecting said nozzle with said float bowl, a mixing chamber into which said nozzle discharges, an air inlet valve for said mixing chamber, a dashpot for said valve, a throttle valve controlling communication between said mixing chamber and an intake manifold of an engine to which said carburetor is adapted to be attached, an idling jet on the engine side of said throttle valve, a needle valve for adjusting said idling jet, a passage connecting said idling jet with said float bowl, means connecting said passage with said mixing chamber above said throttle valve, a flow restriction in said passage, the absolute pressure at said idling jet and in said mixing chamber being greater under certain conditions of carburetor operation than the absolute pressure in said float bowl whereby under said conditions of carburetor operation back bleed into said float bowl through said passage would normally occur and flow control means in said passage preventing back bleed therethrough, said flow control means being designed and arranged to be overcome by suction at said idling jet when said engine is idling.

ROBERT F. BRACKE.
